BOTTLE DISPENSING COOLER

Robert E. Baker, Muncie, Ind., assignor to Glass-cock Brothers Mfg. Co., Muncie, Ind., a corporation of Indiana

Application June 21, 1933, Serial No. 676,829

4 Claims. (Cl. 220—9)

My invention relates to improvements in dispensing coolers for bottle beverages and has for one of its objects the construction of a storage cooler which may be constructed of comparatively light material or light gage metal and which at the same time will have the rigidity of construction and wearing qualities of structures constructed of much heavier gage material or metal. Another object of my invention is to provide a structure which may be cheaply manufactured, but which, in spite of the lowered cost of manufacture, will have the same advantages in structural rigidity and structural finish as structures heretofore made which have cost more to manufacture.

For the purpose of disclosing my invention I have illustrated certain embodiments thereof in the accompanying drawings in which:

Fig. 1 is a plan view of a structure embodying my invention;

Fig. 2 is a side elevation partly in section;

Fig. 3 is a sectional view taken on line 3—3 of Fig. 1;

Fig. 4 is a sectional view taken on the line 4—4 of Fig. 2;

Fig. 5 is a sectional view taken on the line 5—5 of Fig. 2;

Fig. 6 is a sectional view taken on the line 6—6 of Fig. 5;

Fig. 7 is a sectional view taken on line 7—7 of Fig. 2;

Fig. 8 is a sectional view taken on the line 8—8 of Fig. 2;

Fig. 9 is a perspective view of a portion of one of the vertical legs showing the socket for receiving a transverse brace member;

Fig. 10 is a perspective view showing another form of socket;

Fig. 11 is a perspective view of the end of one of the intermediate horizontal braces;

Fig. 12 is a perspective view of the end of one of the bottom horizontal braces;

Fig. 13 is a side elevation partly in section of another form of my invention;

Fig. 14 is an end view thereof partly in section;

Fig. 15 is a sectional view on the line 15—15 of Fig. 13;

Fig. 16 is a sectional view on the line 16—16 of Fig. 13, and

Fig. 17 is a sectional view on the line 17—17 of Fig. 13.

In the structure illustrated, referring now more particularly to that structure illustrated in Figs. 1 to 12 inclusive, I preferably form a self-contained rigid frame consisting of four corner posts

each of which comprises an angle member 1 the edges of which are bent to incline inwardly as at 2 and then as at 3 in a direction parallel with the angle portions 4. This provides an extremely rigid vertical member and these vertical members are connected together intermediate of their tops and bottoms by horizontal angles 5, one leg 6 of which extends vertically and the other leg 7 extends horizontally and is faced inwardly, whereby the four inwardly facing legs of the intermediate braces form a rectangular platform interior of the frame-work. The vertical leg of each of the intermediate horizontal members is likewise inclined inwardly as at 8 and then parallel as at 9 with the portion 6 of the leg. At the ends the transverse member has the ends of the horizontal portion left short and the ends of the parallel member 9 left short to provide a tongue 10 which takes into a slot 11 formed, in the inwardly-bent portion 2 of the vertical leg. After the tongues 10 have been inserted in their slots 11 the intermediate horizontal braces may be rigidly connected to the vertical legs by rivets 12 or, if desired, the parts may be rigidly connected together in other manners as by welding. The corners of the inturned horizontal portions 7 of the intermediate horizontal members are locked together by means of preferably rectangular locking plates 13 which are rigidly secured in their respective corners to the intermediate horizontal bracing members by rivets 14, or if desired, by welding.

In addition to the intermediate horizontal members the legs are connected together at their bottoms by cross horizontal braces 15 having their top and bottom edges inturned or inclined inwardly as at 16 and then extending as at 17 in a direction parallel with the sides of the braces. These bottom transverse braces are likewise provided with tongues 18 adapted to take into slots 19 in the portion 2 of the vertical legs and be riveted in position by suitable rivets as at 19, or in place of the rivets, welding may be resorted to.

At each corner I provide a brace 20 having 45 tongues 21 and 22 lying parallel with and abutting against the bottom transverse braces and riveted thereto as at 23, or welded thereto if preferred.

The above structure, it will be noted, provides an extremely rigid frame as well as assembled frame work. Supported within this frame work is a suitable tank or tub 25. Preferably, in mounting this tub, the same is surrounded by insulating material and to this end I provide a 50

bottom slab of insulating material 26 which rests on the four inturned legs 7 of the intermediate horizontal braces. Interposed between the corner angles are suitable panels or slabs of insulating material 27, which may readily be inserted in position by slipping the same down from the top, and these side panels are preferably faced with removable panels 28 of sheet metal, which, like the insulating panels, may be sleeved into position from the top. With the outer panels and the insulating panels in position the tub 25 may readily be slipped into position from the top and an assembled construction is thus readily produced. For capping the top of the tub and top edges of the insulating panels I provide a rectangular top member preferably channel shaped in cross section and having one leg 29 embracing the top edge of the tub and the other leg 30 embracing the upper ends of the corner posts 1 as well as the panels 28, the outer leg 30 having a portion 31 inclined inwardly to abut against the panel and follow the contour of the leg.

This top frame may, if desired, after the parts have been assembled, be riveted or otherwise secured in position.

For closing the tub I provide a suitable cover member 31a lined with suitable insulating material and provided with any desirable handle, and for draining the excess water from the tub 25 I provide a suitable drain pipe 32.

In the structure illustrated in Figs. 13 to 17 inclusive, I have illustrated an embodiment of my invention in a slightly different form of dispenser. In this structure the four corner posts 1a are substantially like those illustrated in Figs. 1 and 2. The intermediate cross braces or horizontal braces 5a are substantially the same as those illustrated in the structure shown in Figs. 1 and 2, with the exception, however, that the portion 9a buts against the portion 3a of the leg and is welded at the joint 12a instead of being riveted in position as is the case in Figs. 1 and 2.

At the ends of the structure a pair of additional transverse braces 33 are arranged between the legs beneath the cross braces 5a, and these supplemental braces constitute channel members riveted as at 34a to the inner faces of the corner posts.

The bottom braces preferably consist of side channels 34 having their horizontal leg 35 extending inwardly and the vertical leg 36 riveted to the inside face of the corner posts. The end bottom bracing members constitute channel members 37 extending between the side bracing angles at the bottom and being riveted as at 37a to the corner posts. This give an extremely rigid structure and by throwing across, between the side angles, a pair of channels 38 and 39, which may be riveted or welded to the side angles, a suitable platform is provided for a mechanical refrigerating unit, in event such unit is desirable to be used. Immediately above the bottom bracing angles corner braces 40 are welded or otherwise secured to the corner posts to give additional rigidity at this point.

The top frame is substantially like that illustrated in Figs. 1 and 2 and the assembly of the tub and insulating material is the same. The structure being somewhat larger, a cover is provided in two sections instead of a single section, the sections being hinged together.

I claim as my invention:

1. In a bottle dispensing cooler, a supporting frame comprising four corner posts each comprising an angle having its edges offset to provide shoulders, horizontal braces arranged intermediate the top and bottom of the corner posts, each comprising an angle having one leg extending vertically and the other horizontally and facing inwardly, tongues on said vertical legs, and said shoulders on the corner posts having vertical slots in their faces receiving said tongues, the ends of said horizontal legs abutting the shoulders on the corner post, and means for securing said braces to said corner posts, a tub supported on said inwardly-extending horizontal legs, insulating material surrounding said tub and held in position by said corner posts and a top trim covering the upper edges of said tub and insulating material.

2. In a bottle dispensing cooler a frame comprising four corner posts each comprising an angle having its edges offset inwardly to provide shoulders, horizontal braces disposed intermediate of the top and bottom of the posts comprising angles having one leg extending vertically and a portion of the edge of said leg offset inwardly and the other leg extending horizontally and inwardly, tongues on said vertical legs and vertical slots in the shoulders of said corner posts for receiving said tongues, the ends of the horizontal legs abutting the shoulders of the corner posts, and the edges of the offsets on the vertical legs abutting the offset edges of the corner posts, and means for securing said braces to said corner posts, a tub supported in said frame on said inwardly-extending legs, insulating material surrounding said tongues and held in position by said corner posts, and a top trim covering the upper edges of said tub and said insulated material.

3. In a bottle dispensing cooler, a frame comprising four corner posts each comprising an angle having its edges offset to provide shoulders, intermediate braces comprising angle members having one leg extending vertically and the other horizontally and facing inwardly, tongues on said vertical legs extending into vertical slots in the faces of said shoulders of said corner posts, means for securing said brace to said corner posts, corner pieces secured to the adjacent ends of the horizontal legs, side and end braces connected to the bottoms of said corner posts, a tub supported in said frame resting on the inwardly-extending legs of the angle members and insulating material surrounding said tub and held in position by said corner posts and a top trim covering the upper edges of said tub and said insulating material.

4. In a bottle dispensing cooler, a frame comprising four corner posts, each comprising an angle having its edges offset to provide shoulders, braces extending between said corner posts having tongues at their opposite ends adapted to be received by vertical slots in the faces of the shoulders of said corner posts, means for securing said braces to said corner posts, corner pieces secured to the adjacent ends of the horizontal legs, a tub supported within said frame and insulating material surrounding said tub.
